UNITED STATES PATENT OFFICE.

VICTOR L. ROBESON, OF CINCINNATI, OHIO, ASSIGNOR TO LOUIS L. LOEB, OF CINCINNATI, OHIO.

FOOT REST.

Application filed May 31, 1921. Serial No. 473,951.

To all whom it may concern:

Be it known that I, VICTOR L. ROBESON, a citizen of the United States, residing in the city of Cincinnati, in the county of 5 Hamilton of the State of Ohio, have invented certain new and useful Improvements in Foot Rests, of which the following is a specification.

My invention relates to foot rests adapted 10 to be secured to the wall, or any other suitable surface, and upon which the foot may be placed when it is desired to shine or brush the shoes.

It is the object of my invention to provide a rest for the foot when shining or 15 brushing shoes, readily adapted to be swung out of the way after using, of simplified construction and great strength, and also to provide a means thereon for holding 20 the cloth used in shining shoes.

My invention consists of a foot member pivotally mounted on a stationary member, and having a stay member between them pivotally connected to one of the members 25 and slidably connected to the other of the members, and also in the supporting means for the cloth.

My invention further consists in the parts, and combination and arrangement thereof 30 as herein described and claimed.

In the drawing:

Fig. 1 is a perspective view of my improved device in open relation and shown secured to a wall.

Fig. 2 is a similar view but showing the parts in closed relation.

Fig. 3 is a horizontal cross section of the same taken on the line 3—3 of the Fig. 1 and;

Fig. 4 is a vertical cross section of the same taken on the line 4—4 of Fig. 3.

In the embodiment of my invention as illustrated and showing a preferred construction of sheet metal, a wall plate 10 has formed thereon lugs 11 having holes 12, in which a pin 13 is carried. The pin has upset ends 14 which retain the same in the lugs. A foot plate 15 comprises a channel 16 having side flanges 17 thereon. The 50 foot plate has holes 18 in vertical walls 19 of the channel adjacent one of its ends through which the pin 13 passes. In this manner the foot plate is made to swing about the pin, and may either be placed 55 in closed relation against the wall plate or

held in open position at an angle thereto by a stay member 20 hereafter described. The side flanges are cut away at the end adjacent the pin as indicated at 21 to provide clearance for the lugs 11.

The stay member 20 comprises tension rods 22 integrally joined by a yoke 23. The tension rods further have outwardly turned ends 24, which are received in holes 25 in the vertical walls 19 of the channel intermediate of its ends. The yoke is slidably retained behind a strap 26 and in a slot 27 formed between the same and the outer surface of the wall plate. I prefer to form the strap by pressing the same from the body 70 of the wall plate which leaves it integrally connected thereto by upper end section 28 and lower end section 29 respectively. The yoke 23 and the tension rods 22 form a loop about the strap which hold the stay member 75 against lateral movement.

My improved device may be secured to a wall as by screws 40 passing through holes 41 in the wall plate.

The foot plate further has a hook 32 thereon adapted to hold a cloth indicated at 33. The hook is formed by stamping the same from the bottom wall 34 of the channel, and comprises a rounded tang 36 integrally connected to the bottom wall by an angular 85 portion 37. A space 38 is thus formed between the bottom wall and the tang in which the cloth is adapted to be carried.

It being assumed that the device has been previously placed in closed relation (see 90 Fig. 2) and it is desired to utilize the same in brushing the shoes, the foot plate is pulled outwardly and downwardly. This action compels the outwardly turned ends 24 of the stay member to rotate in the holes 25 95 which also causes the yoke 23 to travel downward in the slot 27 behind the strap 26. The yoke is limited in its downward movement by the lower end section 29, where it comes to rest, and thereby in turn limits 100 the downward movement of the foot plate. The foot plate is thus firmly supported in position. The foot may then be placed on the foot plate, the weight carried thereby being transferred to the wall plate through 105 the medium of the stay member 20. In this manner considerable weight may be carried by the foot plate without undue strain on the pins 13, or distortion of the parts. The channel form of the foot plate permits the 110

same to be made of comparatively thin material and yet be strong and durable. The foot plate may afterwards be returned to its position against the wall plate, the yoke of the stay member traveling upward in the slot. The stay member and the strap 26 is adapted to be received within the channel 16 when in closed position. When thus closed my improved device presents a very neat appearance and occupies very little space.

What I claim as new and desire to secure by Letters Patent, is:

1. In a device of the character described, 15 a stationary plate having a slot therein, a channel member pivotally mounted on said stationary plate, and a stay member having one of its ends pivotally connected to said channel member and the other of its ends 20 slidably retained in said stationary plate.

2. In a device of the character described, 25 a stationary plate, lugs thereon, a pin in said lugs, a channel member pivoted about said pin, flanges on said channel member, apertures being formed in said channel member intermediate of its ends, a stay member comprising tension rods, a yoke forming a connection between said tension rods, said tension rods having outwardly turned ends 30 pivotally received in said apertures, and a strap in said stationary plate on which said yoke is slidably retained.

3. In a device of the character described, 35 a wall plate, a foot plate pivotally connected to said wall plate, said foot plate comprising a channel consisting of side walls and a bottom wall, said side walls having apertures,

and flanges on said side walls, said wall plate having a slot therein formed by pressing outwardly a portion thereof, a supporting connection comprising tension rods, a yoke integrally connecting said side rods and slidably retained in said slot, and outwardly turned ends on said tension rods pivotally received in said apertures, and a hook on 45 said foot plate formed by pressing out a portion of said bottom wall of said channel.

4. In a device of the character described, a wall plate, a pair of lugs on said plate formed by pressing portions upward therefrom, a pin secured in said lugs, a raised and integrally connected strip on said wall plate formed by pressing outwardly a portion thereof, said raised strip and said wall plate forming a slot there-between, a foot plate 55 comprising a channel consisting of side walls and a bottom wall, flanges on said side walls having portions thereof cut away adjacent one end, said side walls having apertures adjacent said cutaway portions wherein said 60 pin is rotatably received in said side walls spaced from said first named apertures, a stay member comprising tension rods and a yoke integrally connecting said tension rods, and slidably retained in said slot by said 65 raised strip on said wall plate, and outwardly turned portions on said tension rods pivotally received in said second named apertures in said side walls of said channel in said foot plate, and a hook on said foot 70 plate formed by pressing outwardly a portion thereof.

VICTOR L. ROBERSON.
